SANDING ATTACHMENT FOR DRILL
PRESSESAlbert L. Carey and Justin V. Anslinger,
Kankakee, Ill.

Application February 15, 1947, Serial No. 728,798

9 Claims. (Cl. 51—241)

1

The present invention relates to an attachment for a drill press whereby a drill press may be used as an oscillating spindle sander.

The main object of the invention is to provide a sander which may be secured to a drill press without the use of clamps, special attaching brackets, or other loose parts. More specifically, it is an object of the invention to provide a unitary sanding attachment for a drill press.

A further object of the invention is to provide a sanding attachment which is so constructed that it may be mounted on a drill press by use of the ordinary depth gauge of the drill press.

Applicants have discovered that a sanding cylinder, specifically a cylinder formed of a helically wound sanding sheet if snugly fitted on a smooth faced rod secures itself against relative movement on the rod and remains secured thereto against removal except against hand removal by a slow rotation and axial pull. It is therefore both an object and an advantage of the invention to provide a sanding drum consisting of a smooth faced rod and a sanding cylinder, preferably a helically wound sanding sheet, snugly fitted on the rod and solely secured thereby against movement relative to the rod during the use of the sanding drum.

Other and further objects and advantages of the invention will be apparent from the following description when taken in connection with the accompanying drawing.

Fig. 1 is a perspective view in elevation of the sanding attachment secured to a standard drill press.

Fig. 2 is a view in vertical section through the attachment and in fragmentary vertical section through the drill press showing the manner of attachment thereon.

Fig. 3 is a view in horizontal section taken along the line 3—3 of Fig. 2.

Fig. 4 is a fragmentary view in vertical section taken along the line 4—4 of Fig. 2.

As shown in the drawings, a sanding attachment embodying the invention is designed for attachment to a standard drill press 4 having the usual tool receiving rotary chuck 6, a depth gauge 8 which extends upwardly from a clamping collar 10 secured to the rotary and manually depressible spindle 12. The standard drill press is also provided with a work table 14 secured by a horizontal pivot to a clamping collar 16 on the press column 18. This pivoting of the table 14 permits, as is well known, angular adjustment of the table to differently inclined positions.

The attachment 2, as best shown in Figs. 2 to 4,

2

preferably comprises a housing or support 20 including a casting having one open side wall which may be closed by a cover plate 22 suitably bolted or otherwise secured to the housing casting. The support or housing 20 may be formed with an integral laterally extending bracket portion or lug 24 drilled to provide a suitable aperture 26 to receive the free end of the depth gauge 8 when the same is inverted on the clamping collar 10 as shown in the drawings. The support or housing is secured to the depth gauge or rod 8 by being clamped between the depth controlling and clamping nuts 28 and 30 of the depth gauge.

The housing 20 is provided in its upper and lower ends with apertured bosses 32 and 34 receiving bearings 36 in which is journaled a first spindle 38 receivable in the chuck 6 of the drill press for rotation thereby.

The housing is also provided in its upper and lower ends in spaced relation to the bosses 32 and 34 with a second pair of aligned bosses 40 and 42 apertured to receive similar bearings 44 in which is journaled a second spindle 46.

The spindle 46 is also journaled in a bearing 48 mounted in an aperture of a lug or bracket 50 extending inwardly from, and formed integrally with, a side wall of the housing 20. The spindle 46 is journaled in these bearings 44 and 48 for both rotary motion and vertical reciprocation.

The bearing 48 is mounted on a lug 50 in such manner that its annular flange 52 rests thereon and forms a seat for a spur gear 54 splined to the spindle 46 by means of a pin or set screw 56 in the hub of the gear and received in the longitudinal key slot 58 of the spindle 46. The gear 54 meshes with and is driven by a like gear 60 fixed to the spindle 38 as by the set screw 62. It will be evident that the spindle 38 causes rotation of the spindle 46 by means of the gears 60 and 54.

Spindle 38 is also provided adjacent the lower end of the housing with a worm gear 64 having a reduced hub portion 66 interfitted with a collar 68 having an enlarged axial opening at one end to receive the hub 66 of the worm gear. The collar 68 and worm gear 64 are secured to the spindle 38 by a pin 70 fitted in transverse openings in the collar and passing through aligned openings in the hub of the worm gear and the spindle.

The worm gear 64 intermeshes with and drives a worm wheel 72 journaled on a pin 74 press fitted in the aperture of a boss 76 cast integrally with the side wall of the housing 20. The worm wheel 72 is provided with an eccentric pin 78 re-

ceived in a slot 80 of a slotted yoke which consists of a block 82 loosely mounted on the spindle 46 and held against rotation with the spindle by engagement of the confronting faces of the block and worm wheel. The yoke is held in fixed position against movement longitudinally of the spindle by means of clamping collars 84 pinned to the spindle 46.

It is to be noted that the worm wheel rotates about an axis which is normal to the axis of the spindle 46 and that the axis of rotation of the worm wheel is offset slightly from a vertical plane which includes the axis of rotation of the spindle 46. This offsetting of the two axes assures smooth reversal of the movement of the spindle 46 as it reaches its opposite extremes of reciprocating movement.

The spindle 46 extends below the housing 20 to receive a sanding drum preferably consisting of a smooth faced rod 88 detachably secured to the spindle as by set screw 90. The sanding cylinder 92, which preferably consists of a standard helically wound sanding sheet formed into a permanent cylinder, snugly fits on the smooth faced rod 88. Applicants have discovered that a sanding cylinder snugly fitted on the rod requires no other holding means and that it will not come loose from the rod or move relative to the rod during use, even though a maximum of pressure is exerted by the work against the face of the sanding cylinder. The cylinder may, however, readily be removed by manually turning the cylinder at a slow rate while holding the rod 88 stationary if at the same time a slight axial pull is exerted on the sanding cylinder.

To mount and operate the attachment, the depth control gauge 8 which normally extends upwardly from the ring 10 is released therefrom and resecured thereto in an inverted position. The clamping nut 30 is then removed from the now lower end of the depth control gauge 8 and the lug portion 24 of the housing 20 passed over the lower end of the rod. The clamping nut 30 is then tightened against the lower surface of the lug so that the housing is secured to the rod between the nuts 28 and 30. At the time the housing lug is placed on the rod, the spindle 38 is introduced into the chuck 6 and the chuck tightened so that it is in proper driving engagement with the spindle 38.

The sanding drum having been mounted on the lower end of the spindle 46, the work table 14 is adjusted to align one of the holes therein, usually the central hole 15, with the sanding drum so that the drum may pass down through the work table to sand the wall of a hole or the internal or external edge surface of work placed on the work table. It will of course be evident that the table 14 may be adjusted to any desired inclined position to sand an inclined edge or surface of the work.

As the chuck 6 of the drill press is rotated, the spindle 38 is rotated thereby to effect, through the gears 60 and 54, simultaneous rotation of the spindle 46 at substantially the same speed. Simultaneously with its rotation, the spindle 46 is caused to reciprocate vertically at a much lower rate of speed. This reciprocation is effected by the worm gear 64 on the spindle 38 which rotates the worm wheel 72 and the latter by means of the eccentric pin 78 reciprocates the slotted yoke 82 at a speed determined by the gear reduction afforded by the worm gear 64 and worm gear 72. Thus, the sanding drum is caused to rotate at a relatively high speed while

simultaneously reciprocating vertically at a much lower speed to effect the desired sanding operation.

It will be evident that applicants have provided a relatively simple, inexpensive and rugged sanding attachment of the oscillating spindle type having the advantages and fulfilling the objects of invention heretofore set forth.

While certain specific structures have been disclosed herein for the purposes of illustrating our invention, it will be apparent that variations and changes may be made without departing from the spirit and scope of the appended claims.

What we claim is:

1. In combination with a drill press having a chuck and a stationary rod suspendable from the frame of the press in close parallel relation to the chuck, an attachment comprising a unit including a housing having a bracket extending laterally therefrom for attachment to said rod, a spindle mounted in said housing extending thereabove for insertion in said chuck, a second spindle rotatably and reciprocably mounted in said housing and extending therebelow, gear means in said housing interconnecting said shafts for causing rotation of the second spindle on rotation of the first spindle, and motion converting mechanism mounted in said housing and interconnecting said spindles for causing reciprocation of the second spindle on rotation of the first spindle, and a rotatable and reciprocable tool mounted on the portion of the second spindle projecting beneath said housing.

2. A drum sander comprising a smooth faced rigid rod having a uniform and constant cross-sectional area and a sanding cylinder internally smooth-faced and snugly fitting the rod and solely secured thereby against movement relative to the rod.

3. A drum sander comprising a smooth faced rigid rod having a constant cross-sectional area and a helically wound cylinder of an abrasive sheet having a smooth, internal face and snugly fitting the rod and solely secured thereby against movement relative to the rod.

4. A sanding attachment for a drill press having a chuck and a gauge, said attachment comprising a unit, including a housing having an integral laterally extending lug apertured to receive the depth gauge when inverted for mounting of the housing thereon, a first spindle journaled in the housing and extending from the upper end thereof for insertion in the chuck of the drill press, a second spindle rotatably and reciprocably mounted in the housing and projecting therebelow, means interconnecting the spindles for causing rotation of the second spindle on rotation of the first spindle, a disk having an eccentric pin mounted in said housing for rotation about an axis substantially normal to the axis of rotation of the second spindle, a slotted yoke loosely mounted on the second spindle and secured against relative movement in a direction longitudinally thereof, the eccentric pin on the wheel interfitting in the slot of said yoke, and means interconnecting the first spindle and said wheel causing rotation of the wheel on rotation of the first spindle, whereby the second spindle is simultaneously rotated and reciprocated, and a sanding drum mountable on the portion of the second spindle projecting below said housing.

5. A sanding attachment for a drill press having a chuck and an invertible depth gauge, a housing having an integral, laterally extending lug apertured to receive the depth gauge when

inverted for mounting the housing on said gauge, a first spindle journaled in the housing and extending from the upper end thereof for insertion in the chuck of the drill press, a second spindle rotatably and reciprocably mounted in the housing and projecting from the lower end thereof to receive a sanding drum, intermeshing gears on the spindles within the housing and adjacent one end of the housing for causing rotation of said second spindle upon rotation of the first spindle, a worm wheel mounted in the housing adjacent the opposite end of the housing for rotation about an axis normal to the axis of the second spindle, a worm gear secured to the first spindle and meshing with the worm wheel, an eccentric pin on the worm wheel, a slotted yoke receiving the pin and loosely journaled on the second spindle but secured thereon against axial movement for causing reciprocation of the second spindle on driving of the worm wheel by the worm gear.

6. In combination with a drill press having a rotary chuck and a supporting frame, an attachment comprising a support having an apertured bracket for ready attachment of said support to said frame and detachment of said support from said frame, a spindle rotatably mounted on said support and adapted to be inserted in said chuck for rotation thereby, a second spindle rotatably mounted adjacent to and parallel to said first spindle, said second spindle being reciprocably mounted on said support, means interconnecting said spindles whereby to cause rotation of said second spindle upon rotation of said first spindle, and means interconnecting said spindles whereby said second spindle is reciprocated in said support upon rotation of said first spindle.

7. In combination with a drill press having a rotary chuck and an invertible depth gauge, an attachment comprising a support apertured for attachment to the depth gauge when said gauge is inverted, a first spindle rotatably mounted on said support and projecting thereabove for insertion in said chuck to be rotated thereby, a second spindle rotatably and reciprocably mounted on said support adjacent to and parallel to said first spindle, said second spindle extending below said support and being adapted to receive a work tool, means interconnecting said spindles whereby said second spindle is rotated upon rotation of said first spindle, and means interconnecting said spindles whereby said second spindle is reciprocated within said support upon rotation of said first spindle.

8. An apparatus comprising a housing, a first spindle journaled in the housing and extending from the upper end thereof for attachment to a driving means, a second spindle rotatably and reciprocably mounted in the housing and pro-

jecting therebelow, means interconnecting the spindles for causing rotation of the second spindle on rotation of the first spindle, a disk having an eccentric pin mounted in said housing for rotation about an axis substantially normal to the axis of rotation of the second spindle, a slotted yoke loosely mounted on the second spindle and secured against relative movement in a direction longitudinally thereof, the eccentric pin on the wheel interfitting in the slot of said yoke, and means interconnecting the first spindle and said wheel causing rotation of the wheel on rotation of the first spindle, whereby the second spindle is simultaneously rotated and reciprocated.

9. A mechanism comprising a housing, a first spindle journaled in said housing and extending from the upper end thereof for attachment to a driving means, a second spindle rotatably and reciprocably mounted in said housing and projecting from the lower end thereof to receive a tool, intermeshing gears on the spindles within the housing and adjacent one end of the housing for causing rotation of said second spindle upon rotation of the first spindle, a worm wheel mounted in the housing adjacent the upper end of the housing for rotation about an axis normal to the axis of the second spindle, a worm gear secured to the first spindle and meshing with the worm wheel, an eccentric pin on the worm wheel, a slotted yoke receiving the pin and loosely journaled on the second spindle and secured thereon against axial movement for causing reciprocation of the second spindle on driving of the worm wheel by the worm gear.
